UNITED STATES PATENT OFFICE

GUSTAV A. LEPKE, OF LITTLE NECK, NEW YORK

DESIGN FOR A RUBBER BATHTUB MAT

Application filed November 28, 1930. Serial No. 37,833. Term of patent 14 years.

To all whom it may concern:

Be it known that I, GUSTAV A. LEPKE, a citizen of the United States of America, residing in Little Neck, in the county of Nassau and State of New York, have invented a new, original, and ornamental Design for a Rubber Bathtub Mat, of which the following is a specification, reference being had to the accompanying drawing, forming a part thereof, in which—

Figure 1 is a top plan view of a rubber bathtub mat, compared to full size substantially as 1 is to 4, showing my new design; the dash and dot lines at the bottom of this figure merely indicating that the border is continued around the entire mat;

Fig. 2 is a bottom plan view of the same, compared to full size substantially as 1 is to 4;

Fig. 3 is a fragmental top plan view of the same, compared to full size substantially as 3 is to 2, showing the configurations formed on the entire upper face of the mat;

Fig. 4 is a fragmental bottom plan view, compared to full size substantially as 3 is to 2, showing the configurations formed on the entire lower face of the mat; and

Fig. 5 is a section on the line 5—5 of Fig. 4.
I claim:

The ornamental design for a rubber bathtub mat, as shown and described.

GUSTAV A. LEPKE.
